UNITED STATES PATENT OFFICE.

JOHN C. DOLGONAS, OF CHICAGO, ILLINOIS, ASSIGNOR OF ONE-THIRD TO SAMUEL S. DOLGONAS AND TWO-THIRDS TO HIMSELF, BOTH OF CHICAGO, ILLINOIS.

DEVICE FOR COOLING HANDKERCHIEFS.

1,151,573.

Specification of Letters Patent. Patented Aug. 31, 1915.

Application filed November 6, 1914. Serial No. 870,603.

To all whom it may concern:

Be it known that I, JOHN C. DOLGONAS, a citizen of the United States, residing at Chicago, in the county of Cook and State of Illinois, have invented certain new and useful Improvements in Devices for Cooling Handkerchiefs, of which the following is a specification, reference being had to the accompanying drawings.

10 My invention relates to devices for cooling handkerchiefs, and it has for its object the provision of a new and improved form and construction of device for this purpose. In many cases of illness involving congestion, 15 fevers or headaches, it is highly important that properly cooled handkerchiefs or other appropriate cloths be applied to the affected parts for the relief of the patient. In many instances it is practically impossible for the 20 nurse or other attendant to change the cooling cloth as often as is necessary for the best results, and it has therefore been my object to provide a cooling device which can be placed within convenient reach of a patient 25 and which will retain its efficiency for a considerable length of time, the arrangement of the device being such that the patient himself can readily procure a properly cooled cloth for making the necessary change. The 30 means by which I have accomplished this result are illustrated in the accompanying drawings and are hereinafter specifically described. That which I believe to be new is set forth in the claims.

35 In the drawings, Figure 1 is a side view of my improved device, showing one side of the device opened; Fig. 2 is an end view of the device shown in Fig. 1 as seen from the left in said figure; Fig. 3 is a side view similar to Fig. 1, but showing the device in normal closed condition, the parts being broken away at one corner to better illustrate the construction; and Fig. 4 is a cross-section taken on line 4—4 of Fig. 3.

40 In the drawings, 10 indicates a cylinder closed at one end and having a cap 11 removably mounted upon its other end by means of screw threads. The cylinder 10 is provided at each end with a pair of standards 45 12—13 by which it is adapted to be supported in proper position upon a table or any other level support. The cylinder 10 is also provided with bars 14—15 suitably attached thereto at its ends and rising therefrom, said bars being turned at their upper

ends for engaging a chair back or other suitable support. Near their upper ends the bars 14—15 are connected by a longitudinally-extending bar 16. As best shown in Fig. 2, the bars 14—15 are provided with strips 17 of velvet, rubber, or other suitable material, for affording a proper bearing of the bars 14—15 upon the chair or other support from which the device is hung. The cylinder 10 is also provided with two lugs 18—19, near its ends, adapted to support a longitudinally-extending pivot-pin 20. Pivotally mounted upon the pin 20 are two semi-cylindrical plates 21—22 adapted to be closed down about the cylinder 10, as shown in Figs. 3 and 4, between the flanges 10^a and 10^b extending from said cylinder. As will be readily understood, either of the plates 21—22 can be opened up into position above the cylinder 10 so as to permit free access to said cylinder. In Figs. 1 and 2 the bars 14—15 are shown broken away at points intermediate their ends, indicating that the upper ends of said bars, together with the longitudinally-extending bar 16, are shown in lowered position relative to the cylinder 10 compared to the position normally occupied by such bars. In practice, the bar 16 is to be located sufficiently above the cylinder 10 to permit the semi-cylindrical plate 22 to be turned upward above the cylinder so as to be held by its own weight in raised position, as will be readily understood. Each of the plates 21—22 is rolled at its free edge whereby said plate is adapted to be held yieldingly in closed position by its engagement with a spring-clip device 23 depending from the bottom of the cylinder 10 at about its middle point.

45 In use, the cylinder 10 is to be filled with ice or some other suitable cooling agent, the cap 11 being temporarily removed for this purpose. A plurality of handkerchiefs, towels, or other suitable cloths, such as 24, are then to be placed in position upon the cylinder 10, after which the semi-cylindrical plates 21—22 are to be closed down about the cylinder 10 and the cloths mounted thereon. The device as a whole can then be placed upon a table or other suitable device 50 within convenient reach of the patient, or it can be hung from the back of a chair by means of the bars 14—15, if desired. A drain-pipe 26 is provided at one end of the cylinder 10 adapted to be closed by a cap 55 110

27 secured by means of screw threads upon the pipe 26. As will be readily understood, upon the removal of the cap 27 any surplus of water accumulating in the cylinder 10 as 5 the ice melts therein may be drained off.

By the use of my device there is provided a plurality of properly cooled cloths within convenient reach of a patient, who is enabled to take from the device successively 10 the several cloths contained therein. Even if the patient is too sick or too weak to replace the cloths in position upon the cylinder 10, there is at least a supply of cooled cloths ready for his use for some little time, 15 so that the attendant is enabled to give comparatively much more time to other duties than would be the case if the device were not used.

By reason of the use of the semi-cylindrical plates 21—22 substantially inclosing the cylinder 10 except at its ends and forming chambers about the cylinder between the flanges 10^a and 10^b, the contents of the cylinder is in effect insulated from the atmosphere of the room, whereby the cooling agent 20 is protected from the warmth of the room and the efficiency of the device is thus maintained.

As will be readily understood, by means 30 of my improved device I am enabled to properly cool handkerchiefs or other suitable cloths for the relief of fevers or congestion, whether such cloths are dampened as they ordinarily are in practice or whether 35 they are kept in a dry condition, as would in some cases be preferable.

While I have shown the enveloping or covering plates or hoods 21—22 in semi-cylindrical form so as to inclose the entire periphery of the cylinder 10, it will be understood that I do not limit myself to this particular construction except as hereinafter specifically claimed.

That which I claim as my invention, and desire to secure by Letters Patent, is,—

1. A cloth-cooling device comprising a cylinder adapted to contain a cooling agent and semi-cylindrical plates pivotally mounted on said cylinder and adapted when closed to surround said cylinder but spaced a short 50 distance from the walls thereof, the space between said cylinder and said plates being adapted to receive a plurality of cloths for cooling purposes.

2. A cloth-cooling device comprising a cylinder adapted to contain a cooling agent, semi-cylindrical plates pivotally mounted on said cylinder at one side thereof adapted when closed to surround said cylinder but spaced a short distance from the walls thereof, and a double spring-clip mounted on said cylinder substantially diametrically opposite the pivotal mounting of said plates thereon adapted to receive the free edges of 60 said plates from opposite directions for holding the plate yieldingly in position relative to the cylinder.

JOHN C. DOLGONAS.
